UNITED STATES PATENT OFFICE.

WILLIAM WOOD, OF HARTFORD, CONNECTICUT.

BRICK-MACHINE.

Specification of Letters Patent No. 29,645, dated August 14, 1860.

To all whom it may concern:

Be it known that I, WILLIAM Wood, of the city of Hartford, county of Hartford, and State of Connecticut, have invented new and useful Improvements in the Mode of Constructing Brick-Making Machines; and I do hereby declare that the following is a correct description thereof, reference being had to the accompanying drawing and to

10 the letters of reference marked thereon.

The nature of my invention consists in levers, to press down the piston rod and plate to fill the molds, with arrangements to raise up the same when the mold is filled, 15 also a self acting arrangement for forcing out the brick mold when it is filled, &c.

To enable others skilled in the art to make and use my invention, I will proceed to describe its construction and operation.

20 In the drawings, Figure 1 a front view of the machine; Fig. 2 a side view; Fig. 3 a plan view showing center rod for forcing out the mold; Fig. 4 a side view of the same.

I construct the frame, clay box, the grinding process, piston and press plate, and other parts, in the customary manner.

I make the lever A with a cam shaped lower end, to press on the wheel in the head of the piston rod H, to force down the same 30 and the press plate to press the clay into the mold. The upper part of the lever extends sufficiently high to be acted on by the arms C, in the main shaft D, when revolving, and carry the same forward till it 35 presses the end to allow the arm to pass over.

The lever B, is for raising up the piston and plate after doing the duty of pressing the clay into the mold. The lower end of 40 the lever is attached to the piston rod H, by means of a slot and a series of pins in the rod G, so arranged that the rod can be shifted to adjust and regulate the distance the press plate travels up and down. The 45 upper end of the lever B, is actuated by the arms C, in the same manner as the lever A, and receives the action, instantly, after leaving the lever A, causing the same to depress, and lift up the piston and plate as before 50 stated. The spring lever E, reaches up the same height as the levers A and B, to receive

the action of the revolving arms C after leaving them—(they having filled the mold, and drawn up the press plate.) This lever E comes into operation and at the proper 55 time forces out the filled mold and falls back again to receive another empty mold. This lever E, is attached to the horizontal rod E, e, by a joint on the lower end, and the rod E, e, then connects with the vertical 60 lever f, on the rock shaft F, which gives the vibratory motion to the arm N, which is connected to the central slide K, reaching back to the two friction pulleys P, and the slide K, has a cross head S—to press out the brick 65 mold when filled, the whole actuated by the lever E. Near the top of the lever E, I make a joint and attach a stiff spring T, as a preventative to damage. If there should be an obstruction to the mold coming out, by a 70 stone or otherwise, the extra force required will cause the spring to yield and the arm will bend the lever and pass over till the cause of the obstruction is removed. The spring u is to bring back the lever E and 75 attachments after they have discharged the mold.

What I claim as my invention, and desire to secure by Letters Patent, is—

1. The construction and arrangement of 80 the spring lever E, for throwing out the mold, attached to the rock shaft F, and, actuated by the direct action of the arms C from the main shaft D, in the manner described.

2. The arrangement of the two levers A, and B, one for pressing down the piston and plate for filling the mold, and the other to lift up the same after the mold is filled, in the manner as herein described, being operated by the direct action of the arms C, from 90 the main shaft D, as specified.

3. The adjusting arrangement of the slot, sliding ring and pins G, attached to the piston rod H, and lever B, to regulate the pressure of the piston and press plate, all in the manner and for the purpose as set forth.

WILLIAM WOOD.
